UNITED STATES PATENT OFFICE.

KARL BUNGERZ, OF HEMPSTEAD, NEW YORK, ASSIGNOR TO WESTERN ELECTRIC COMPANY, INCORPORATED, OF NEW YORK, N. Y., A CORPORATION OF NEW YORK.

TELEPHONE RECEIVER.

Application filed December 2, 1920. Serial No. 427,805.

To all whom it may concern:

Be it known that I, KARL BUNGERZ, a citizen of the United States, residing at the town of Hempstead, in the county of Nassau, 5 State of New York, have invented certain new and useful Improvements in Telephone Receivers, of which the following is a full, clear, concise, and exact description.

This invention relates in general to telephone receivers and particularly to that type of receiver which employs no permanent magnet.

General use has in the past been confined to telephone receivers employing permanent 15 magnets in conjunction with electromagnetic coils for influencing the receiver diaphragm. Another type of receiver which is becoming more widely used is that in which no permanent magnet is employed, a constant magnetism being furnished by an electromagnet. Such receivers are usually connected in series 20 with the line, and the current for supplying the magnetism is furnished from the central office. The present invention relates to electromagnet receivers of this type, adapted for use on high efficiency substation circuits.

The object of the invention is to provide a receiver of improved efficiency, and one which may be manufactured economically.

25 In the preferred form of the invention, a magnet structure is provided which comprises an outer iron shell made of a punching, and an inner pole which is made of two punched pieces of silicon steel. These two 35 pieces and the outer iron shell are welded together. The unitary core structure thus obtained is a considerable improvement from a magnetic standpoint, and is also mechanically superior to those now in use.

40 In the drawing, Fig. 1 is a longitudinal section of the telephone receiver setting forth the features of the present invention; Fig. 2 is a perspective view of the assembled magnet poles; and Fig. 3 is a perspective 45 view showing separately the two poles of the magnet.

As is shown in Fig. 1 of the drawing, the receiver is internally a self-contained unit, 50 consisting of the brass cup 4 for mounting the magnetic system and for providing a diaphragm clamping seat. The cup 4 has a flange 5 which forms a seat for the diaphragm 6. The diaphragm is clamped in place by a brass screw cap 7 which engages 55 the threads on the cup 4. The cap 7, which

is made in the form of a grid to protect the diaphragm, engages the circular edge of the receiver casing 8 thereby serving to locate the inner unit within the shell.

The electromagnet of the receiver comprises a coil of wire 9 which is slipped over a core 10 of silicon steel formed of a plurality of separate segments magnetically connected in such a manner as to reduce eddy-current losses. These segments constitute one pole of the magnet. The coil 9 is surrounded by an outer shell 11 consisting of a split cylindrical shell preferably of soft iron, to the flange 12 of which are welded the bases 13 and 14 of the inner pole segments forming pole 10, as shown clearly in Fig. 2. This outer shell 11 constitutes the other pole of the magnet. Silicon steel has been found to possess the necessary magnetic characteristics to render it suitable for the core material, but other materials having such characteristics as to produce the desired result may be used. It is extremely difficult to draw the outer pole 11 from a sheet of silicon steel, and for this reason soft iron is used. It has been found that from a mechanical and an assembly point of view it is most satisfactory to divide the inner pole piece into two sectors, as 13 and 14, more clearly shown in Fig. 3. These sectors are each integrally formed with the corresponding ring segment of the inner pole and are substantially at right angles thereto. In the accompanying drawing the flange 12 of the outer shell 11 is shown welded to the base sectors 13 and 14 of the inner pole 10. Practically the same results may be obtained by fastening the parts together by means of screws threading into the brass resonating cup 4. It may be said, 95 however, that the welds serve the double function of providing for the continuity of the magnetic circuit and of making a single unit of the three parts.

When the magnet unit is mounted in the 100 bell of the receiver, the four screws 15, only one of which is shown, are used for mounting and also serve to insure the continuity of the magnetic circuit by clamping together the component parts of the welded 105 assembly. The coil 9 is held in place with shellac or any other suitable material. The rubber plug 16 which is forced between the ring segments of the inner pole, and is fastened with shellac, serves to maintain the 110

gap between the segments. The coil 9 is placed in position with the leads 17 issuing from the underside thereof rather than from the top, the object being to keep the wires from coming in contact with the diaphragm and from getting in between the diaphragm and the core.

To compensate for the weight of the usual permanent magnets which are omitted in this receiver, a cast lead weight 18 is attached by means of detachable bolts 19 to the back of the cup 4. Binding posts 20 for attaching tubular or spade tips are mounted on a block of insulating material 21 which is held to the receiver cup by the bolts 19 which hold the weight 18 in place.

The unitary core structure herein disclosed is economical and easily constructed. Because of the compactness of the magnet system, it has been possible to design a receiver which, being a self-contained unit, will fit directly into the shell of most receivers in common use, and is held therein by the usual receiver cap 22. Thus the inner unit will function as a telephone receiver even if the outer shell and cap are destroyed.

What is claimed is:

1. In a telephone receiver, a unitary magnet structure comprising an outer pole in the form of a split cylindrical shell, and an inner pole consisting of a plurality of longitudinal cylindrical segments.

2. In a telephone receiver, an electromagnet comprising in combination an inner cylindrically shaped pole made up of a plurality of longitudinal segments, a coil or winding thereon, and a split cylindrical metallic shell encircling said coil and adapted to serve as an outer pole.

3. In an electromagnet core structure, a substantially circular outer pole of magnetic iron and an inner pole of much smaller cross sectional area formed of a plurality of longitudinal silicon steel segments substantially in cylindrical formation centrally disposed within said outer pole.

4. In an electromagnet core structure, a pole comprising a plurality of magnetically separate longitudinal cylindrical segments substantially in cylindrical formation and a base consisting of a plurality of sectors of magnetic material outwardly extending and integrally formed with said corresponding segments and substantially at right-angles thereto.

5. In an electromagnet core structure, a pole comprising a split cylindrical shell of magnetic material having an outwardly extending flange substantially at right-angles thereto and an inner pole having a flange engaging the flange on said outer pole piece and secured thereto.

6. In an electromagnet, an outer pole in the form of a split cylindrical ring, an inner pole consisting of a plurality of magnetically separate longitudinal cylindrical segments, and means between said segments for maintaining the gaps between the segments comprising said inner pole.

7. In a telephone receiver, an internally self-contained speaking unit comprising in combination a diaphragm, a cup, a magnetic system mounted in said cup, said magnetic system comprising a pole in the form of a split cylindrical shell, and a pole formed of a plurality of longitudinal cylindrical segments, and a coil or winding mounted thereon for operating said diaphragm, said coil and second-named pole being disposed within said cylindrical shell.

8. In an electromagnet core structure in combination, a pole comprising a plurality of longitudinal segments of magnetic material substantially in cylindrical formation and a base consisting of a plurality of sectors of magnetic material integrally formed with said segments and substantially at right-angles thereto; and a pole comprising a split cylindrical shell of magnetic material and a flange integrally formed therewith and substantially at right-angles thereto.

9. In an electromagnet core structure, a substantially circular outer pole comprising a split cylindrical shell of magnetic material and a base comprising an outwardly extending flange substantially at right angles thereto, an inner pole formed of a plurality of magnetically separate segments of silicon steel substantially in cylindrical form and having a base consisting of a plurality of sectors of magnetic material integrally formed with said corresponding segments and substantially at right angles thereto, said two poles being so disposed one to the other that the flange of one is in superposition with respect to the base of the other.

In witness whereof, I hereunto subscribe my name this 23rd day of November, A. D. 1920.

KARL BUNGERZ.
